L. C. MILLER

SPUDDING SHOE

Filed June 3 1924

Patented July 28, 1925.

1,547,938

UNITED STATES PATENT OFFICE.

LESTER C. MILLER, OF SKIATOOK, OKLAHOMA.

SPUDDING SHOE.

Application filed June 3, 1924. Serial No. 717,606.

To all whom it may concern:

Be it known that I, LESTER C. MILLER, a citizen of the United States, residing at Skiatook, in the county of Tulsa and State of Oklahoma, have invented certain new and useful Improvements in Spudding Shoes, of which the following is a specification, reference being had to the accompanying drawings.

10 This invention relates to spudding shoes for well drilling apparatus and has for an important object thereof the provision of a spudding shoe having a drilling cable engaging surface constructed to relieve the friction ordinarily applied to the drilling cable.

15 A further object of the invention is to provide a construction of this character in which the drilling cable engaging surface is readily renewable when destroyed or grooved by contact with the cable.

20 A still further object of the invention is to provide a device of this character in which the mounting of these sections is greatly simplified and in which the simplified mounting is extended not only to this cable engaging surface but likewise to the rein mounting of the rope socket by means of which the spudding shoe is operated and 25 to the handle by means of which the shoe is manipulated and placed in position.

25 A still further object of the invention is to provide a device of this character in which the device is made in two sections 30 identical in their construction, so that the cost of production of the device may be very materially reduced and expedited.

35 These and other objects I attain by the construction shown in the accompanying drawings, wherein for the purpose of illustration is shown a preferred embodiment of my invention and wherein:—

40 Figure 1 is a fragmentary side elevation of a drilling rig showing the application of the spudding shoe thereto;

45 Figure 2 is a perspective view of the spudding shoe detached;

50 Figure 3 is a vertical sectional view through the spudding shoe between the sections;

55 Figure 4 is a transverse sectional view on the line 4—4 of Figure 3;

Figure 5 is a transverse sectional view on the line 5—5 of Figure 3;

60 Figure 6 is a perspective of the handle removed.

Referring now more particularly to the drawings, the device consists of two identical sections 10 each having an arcuate edge 11, a straight edge 12 chordal to the arcuate edge 11, the ends of the sections being preferably truncated as indicated at 13. These sections are secured to one another by bolts 14 extending through openings spaced from the arcuate edge thereof and with their arcuate edges coinciding. Adjacent faces of the sections, when in assembled relation, have their arcuate edges rabbeted, as at 15 to provide an inclined bevel from such faces to the arcuate edge, these bevels combining to provide a V-shaped groove 16 in the face of the completed spudding shoe for the reception of a drilling cable generally indicated at 17.

65 Formed in adjacent faces of the sections 10 upon an arcuate line concentric with the edge of the sections is a row of circular sockets, the centers of these sockets lying outwardly of the inner edge of the bevel. These sockets combine to provide bearings 70 for the ends of rollers 19 the peripheries of which intercept the base of the V-shaped groove and receive the pressure of the drilling cable, thus providing rotating surfaces 75 against which the cable may bear preventing grooving or cutting at any one particular point at the base of the groove. As the rollers become worn they may be readily replaced by separating the sections, or those disposed at the ends of the groove, and consequently receiving but slight wear, may be interchanged with those disposed at the center of the groove until the entire lot of 80 rollers is so worn as to become useless.

85 Extending inwardly from the straight face 12 of each of the sections at the adjacent faces thereof are grooves 20, these grooves combining in the assembled position of the sections to provide sockets for the reception of the ends of the arms 21 of a U-shaped handle 22. One groove, of each opposed pair of sections, in assembled relation is provided at the inner end thereof with a socket 23 receiving an angular foot 24 formed upon the end of its receiving arm 21, these angular feet being oppositely directed and, therefore, maintaining the handle rigidly in position upon the shoe. Intermediate these grooves and at the center of each section, the sections have each formed therethrough a bore 25 the inner end of which is enlarged, as at 26, to receive the hub portion 90

27 of a rein receiving shaft 28 the ends of which will project beyond the outer faces of the sections 10 to be engaged by the rein hooks 29 of the reins of a rope socket 30
5 attached to the end of a jerk line 31. It will readily be seen that all of the various sections employed in the construction of the device are readily removable and replaceable in event of wear and that the device
10 may be very cheaply produced due to the fact that the sections 10 are exact duplicates of one another.

It will furthermore be obvious that the construction hereinbefore set forth is capable
15 of a certain range of change and modification without materially departing from the spirit of my invention and I accordingly do not limit myself to such specific structure except as hereinafter claimed.

20 I claim:—

1. In a spudding shoe, a pair of identical sections each having an arcuate edge, the sections being secured face to face with their arcuate edges coinciding, the adjacent faces
25 of the sections being rabbeted at their arcuate edges whereby the sections when combined provide an arcuately curved face having a groove for the reception of a drilling line, and rollers having their ends journaled
30 in adjacent faces of the sections and their peripheries projecting into the groove to receive the drilling line.

2. In a spudding shoe, a pair of identical sections each having an arcuate edge, the

sections being secured face to face with their arcuate edges coinciding, the adjacent faces of the sections being rabbeted at their arcuate edges whereby the sections when combined provide an arcuately curved face having a groove for the reception of a drilling line, said sections each having aligned bores therethrough, the adjacent ends of the bores of the sections being enlarged, and a rein receiving shaft directed through the bores of the sections and having an enlarged hub portion fitting the enlarged portions of the bores.

3. In a spudding shoe, a pair of identical sections each having an arcuate edge, the sections being secured face to face with their arcuate edges coinciding, the adjacent faces of the sections being rabbeted at their arcuate edges whereby the sections when combined provide an arcuately curved face having a groove for the reception of a drilling line, said sections having in adjacent faces thereof and at the edge thereof opposite to said arcuate edges coating grooves providing sockets for the ends of the arms of a U-shaped handle member, said handle member being provided at the ends of the arms thereof with angular feet, one groove of each of said sections having at the inner end thereof a socket for the reception of the foot of the received arm of the handle.

In testimony whereof I hereunto affix my signature.

LESTER C. MILLER.
